UNITED STATES PATENT OFFICE.

WILLIAM M. RHOADS, OF DENVER, COLORADO.

DESIGN FOR A BOOK-COVER.

No. 37,976.

Specification for Design.

Patented May 1, 1906.

Application filed February 20, 1905. Serial No. 246,639. Term of patent 7 years.

To all whom it may concern:

Be it known that I, WILLIAM M. RHOADS, a citizen of the United States of America, residing in the city and county of Denver and State of Colorado, have invented a new, original, and ornamental Design for Book-Covers, of which the following is a specification, reference being had to the accompanying drawing, forming part thereof.

The figure is an elevation of the outside of a book-cover, showing my new design.

I claim—

The ornamental design for a book-cover, as shown.

WILLIAM M. RHOADS.
